PAPER STORAGE SYSTEM

Gerald B. Shelly, 3802 W. Townley Ave., Phoenix, Ariz.

Filed Jan. 29, 1964, Ser. No. 340,958

12 Claims. (Cl. 108—60)

The present invention pertains to paper storage, and more particularly, to paper storage systems of the type useful in those operations requiring collating and the storage of plural stacks of paper each sheet being a duplicate of the remainder of the sheets in that stack.

The presentation of modern technology and devices has brought about a change in the manner that products are presented to potential customers. Specifically, such as in the electrical and electronics industry, it is common to provide what is known as "data sheets" and other descriptive material in more or less loose bound form to potential customers. It is also frequently desirable to store the contents or pages of these publications independent from the remainder of the pages to thereby permit access to the storage area for assembling a portion or portions, and not a complete, publication. In these circumstances, it is customary to provide a file room having bins each of which contains a stack of printed paper each page of which is identical to the remainder of the pages in the stack; that is, all pages of a given number will be contained in the same stack. Collating and assembling of these pages presents several problems particularly when a period of time elapses between the storage of the pages and their subsequent utilization.

The bulk of the stored pages, and their inaccessibility to visual inspection to determine the identity of the individual pages, has given rise to storage problems requiring excessive amounts of space and also requiring extensive publication assembly time; these disadvantages are particularly acute when only a few copies of the publication are to be assembled at a time.

Accordingly, it is an object of the present invention to provide a paper storage system that will provide visibility of a chosen portion of all pages stored in the system.

It is also an object of the present invention to provide a paper storage system that permits convenient access to all individual pages of the publication stored in the system.

It is still another object of the present invention to provide a paper storage system that is adaptable and can be expanded or reduced in capacity in accordance with the requirements of the system.

It is another object of the present invention to provide an inexpensive and nevertheless rugged paper storage system that will achieve maximum utilization of available space.

Further objects of the present invention will become apparent to those skilled in the art as the description thereof proceeds.

Briefly, in accordance with one embodiment of the present invention, shelves are utilized that are parallel and mounted horizontally. The shelving may be the customary shelving used to store other types of material such as books, packages, etc. A plurality of dividers, arranged at an angle relative to and in between corresponding shelves, are provided to separate stacks of pages. The dividers are held parallel to each other and in separated fashion through the expediency of separators positioned intermediate the dividers. Each separator is shaped to provide a parallel abutting surface to one divider, a surface perpendicular to the divider to support paper stored thereon, a surface parallel to and in abutting relation with the bottom shelf, and is also provided with a longitudinal channel so shaped to accept one edge of the next succeeding divider thus maintaining the proper

2

inter-divider space. The present invention may be more readily described by reference to the accompanying drawings in which:

FIGURE 1 is a front elevation of a paper storage system constructed in accordance with the teachings of the present invention.

FIGURE 2 is a plan view of a divider of FIG. 1.

FIGURE 3 is a top view of a separator of FIG. 1.

FIGURE 4 is an end view of the separator of FIG. 3.

FIGURE 5 is an isometric view of a paper storage system constructed in accordance with the teachings of the present invention.

FIGURE 6 is a top view of the dividers of FIG. 1.

FIGURE 7 is a modification of the dividers of FIG. 6.

FIGURE 8 is a modification of the top edge spacing means for the individual dividers of FIG. 1.

FIGURE 9 is an enlarged top and end view respectively of a portion of FIG. 8.

Referring to FIG. 1, a top shelf 10 and a bottom shelf 11 are mounted in parallel spaced-apart fashion in any convenient manner. In the embodiment shown in FIG. 1, the shelves 10 and 11 are mounted through the expediency of a vertical supporting member 12 having notches 13 and 14 for supporting the shelves 10 and 11, respectively. The top shelf includes a plurality of notches 20 that are cut in the shelf 10 transverse to the plane of the drawing and at an angle relative to the top shelf. The notches 20 accommodate a plurality of dividers 21 which are secured to the top shelf 10 by inserting the corresponding divider into one of the notches 20. The dividers 21 are maintained in equidistant relationship relative to each other through the expediency of separators 25, each of which includes a first surface 27 parallel to and in abutting relation with the adjacent divider 21. The separators also each include a second surface 28 extending perpendicularly from the first surface 27 to form a surface for supporting paper 30 placed between adjacent dividers. A third surface 32 extends from the first surface of each of the separators and is parallel to and in abutting relation with the top surface of the bottom shelf 11. A longitudinal channel 35, seen more clearly in FIGURE 4, extends the length of each separator and is shaped to accommodate the lower edge of each of the dividers 21. The separators need not be attached to the bottom shelf and need only be placed in such a manner that the left-most (as shown in FIG. 1) separator is in abutting relation with the supporting member 12, thus preventing the separator from moving to the left. Successive separators need only be placed in abutting relation with the preceding divider to permit the insertion of the next succeeding divider. Only the number of dividers necessary for the present particular application of the invention is necessary; therefore, dividers may be added or removed in accordance with the needs of the application without the necessity of complicated or expensive system modification.

The particular shape of the individual dividers may best be seen by reference to FIG. 2. In FIG. 2 it may be seen that the divider is substantially planar (a flat plane surface) and is notched as shown in FIG. 2 at 40. The notch permits visual inspection of a desired corner of the page and also permits ready access to the pages in a stack. The notch 40 is generally rectangular and is of an appropriate size so that it removes sufficient material from the edge 41 of the divider 21 to reduce the length of the edge 41 to the length of one edge of the paper to be stored in the paper storage system. Thus, referring to FIG. 1, it may be seen that the length of the paper stack 30 is such that it extends to the edge 42 of the notch 40.

Referring to FIG. 6, the dividers 21 are shown as they

would appear from the top if the top shelf were removed. It is noted that the plane of each of the dividers intersects the plane of the top shelf to form a line perpendicular to the longitudinal direction of the top shelf. The modification shown in FIG. 7 may be used to expose selected sections of a sheet, either the same or different sections exposed by the embodiment of FIG. 6, and would alleviate the necessity of providing notches. Referring to FIG. 7, each of the dividers 45 is tilted back to form a plane that is at approximately the same angle to horizontal as the dividers 21 are of FIG. 6. However, the dividers 45 are also angled relative to the longitudinal direction of the top shelf so that the intersection of the plane of the top shelf and the plane of the dividers 45 is a line forming an angle ϕ relative to the longitudinal direction of the top shelf.

Referring to FIGS. 8 and 9, the necessity for providing notches in the bottom of the top shelf is alleviated through the expediency of a plurality of clips 50 secured to the respective dividers 21 by any convenient means such as by riveting as shown in FIGS. 8 and 9. The clips 50 are secured to the corresponding divider 21 and extend therefrom at an angle to provide a parallel surface to the bottom of the top shelf 10. An extension 51 is provided on each clip that extends from the portion of the clip parallel to the shelf 10 into abutting relation with the next adjacent divider 21. The last divider (the one to the right in FIG. 8) may be maintained in position through the utilization of clips of identical design used with the remainder of the dividers; however the clips are nailed or screwed, such as by wood screw 55, to the bottom of the top shelf to prevent the divider from moving to the right. Therefore, using the embodiments shown in FIGS. 8 and 9 the necessity for providing notches in the bottom surface of the top shelf is alleviated, and the dividers may be added or removed at will merely by providing a divider with a clip and a separator.

It will be apparent to those skilled in the art that many modifications may be made from the embodiments chosen herein for illustration. These modifications are especially apparent in consideration of the simplicity of the embodiments shown in FIGS. 8 and 9 since the clips shown and described therein may take a variety of forms; similarly, the dividers 21 and their respective notches 40 may be modified in shape and size to accommodate a variety of paper forms to be stored in the paper storage system of the present invention.

What is claimed is:

1. A paper storage system comprising:

- (A) means defining two substantially parallel planes
- (B) a plurality of dividers parallel to each other and angularly disposed to said parallel planes
- (C) a plurality of separators positioned intermediate said dividers, each including:
  - (1) a first surface parallel to and in contact with one of said dividers
  - (2) a second surface extending from and perpendicular to said first surface
  - (3) a third surface extending from said first surface parallel to and in contact with one of said parallel planes
  - (4) means defining a channel portion extending from said second and third surfaces and shaped to accept one edge of the divider adjacent said one of said dividers.

2. A paper storage system comprising:

- (A) means defining two substantially parallel planes
- (B) a plurality of dividers parallel to each other and angularly disposed to said parallel planes, each divider including:
  - (1) a rectangular planar member
  - (2) means defining a notch removing a corner of said rectangular planar member
  - (C) a plurality of separators positioned intermediate said dividers, each including:

(1) a first surface parallel to and in contact with one of said dividers

(2) a second surface extending from and perpendicular to said first surface

(3) a third surface extending from said first surface parallel to and in contact with one of said parallel planes

(4) means defining a channel portion extending from said second and third surfaces and shaped to accept one edge of the divider adjacent said one of said dividers.

3. A paper storage system comprising:

- (A) means defining two substantially horizontal and parallel planes
- (B) a plurality of dividers parallel to each other and angularly disposed to said parallel planes and extending between said planes, each divider including:
  - (1) a rectangular planar member
  - (2) means defining a notch removing a corner of said rectangular planar member
  - (C) a plurality of separators positioned intermediate said dividers, each including:
    - (1) a first surface parallel to and in contact with one of said dividers
    - (2) a second surface extending from and perpendicular to said first surface
    - (3) a third surface extending from said first surface parallel to and in contact with one of said parallel planes
    - (4) means defining a channel portion extending from said second and third surfaces and shaped to accept one edge of the divider adjacent said one of said dividers.

4. A paper storage system comprising:

- (A) means defining two substantially horizontal and parallel planes
- (B) a plurality of dividers parallel to each other and angularly disposed to said parallel planes and extending between said planes, each divider including:
  - (1) a rectangular planar member
  - (2) means defining a rectangular notch removing a corner of said rectangular planar member
  - (3) said notch removing sufficient material from said corner to reduce the length of one edge of said planar member to the length of one edge of the paper to be stored in said paper storage system
  - (C) a plurality of separators positioned intermediate said dividers, each including:
    - (1) a first surface parallel to and in contact with one of said dividers
    - (2) a second surface extending from and perpendicular to said first surface
    - (3) a third surface extending from said first surface parallel to and in contact with one of said parallel planes
    - (4) means defining a channel portion extending from said second and third surfaces and shaped to accept one edge of the divider adjacent said one of said dividers.

5. A paper storage system comprising:

- (A) means defining two substantially parallel planes
- (B) a plurality of dividers parallel to each other and angularly disposed to said parallel planes
- (C) a plurality of separators positioned intermediate said dividers, each including:
  - (1) a first surface parallel to and in contact with one of said dividers
  - (2) a second surface extending from and perpendicular to said first surface
  - (3) a third surface extending from said first surface parallel to and in contact with one of said parallel planes
  - (4) means defining a channel portion extending from said second and third surfaces and shaped

5

- to accept one edge of the divider adjacent said one of said dividers.
- (D) means for positioning one edge of each of said dividers relative to one of said parallel planes.
6. A paper storage system comprising:
- (A) means defining two substantially horizontal and parallel planes
- (B) a plurality of dividers parallel to each other and angularly disposed to said parallel planes and extending between said planes, each divider including:
- (1) a rectangular planar member
- (2) means defining a notch removing a corner of said rectangular planar member
- (C) a plurality of separators positioned intermediate said dividers, each including:
- (1) a first surface parallel to and in contact with one of said dividers
- (2) a second surface extending from and perpendicular to said first surface
- (3) a third surface extending from said first surface parallel to and in contact with one of said parallel planes
- (4) means defining a channel portion extending from said second and third surfaces and shaped to accept one edge of the divider adjacent said one of said dividers.
- (D) means for positioning one edge of each of said dividers relative to one of said parallel planes.
7. A paper storage system comprising:
- (A) means defining two substantially parallel planes
- (B) a plurality of dividers parallel to each other and angularly disposed to said parallel planes
- (C) a plurality of separators positioned intermediate said dividers, each including:
- (1) a first surface parallel to and in contact with one of said dividers
- (2) a second surface extending from and perpendicular to said first surface
- (3) a third surface extending from said first surface parallel to and in contact with one of said parallel planes
- (4) means defining a channel portion extending from said second and third surfaces and shaped to accept one edge of the divider adjacent said one of said dividers.
- (D) means for positioning one edge of each of said dividers relative to one of said parallel planes comprising:
- (1) clip means attached to said divider and extending therefrom parallel to one of said planes
- (2) means extending from said clip in abutting relation with the next adjacent divider.
8. A paper storage system comprising:
- (A) means defining two substantially horizontal and parallel planes
- (B) a plurality of dividers parallel to each other and angularly disposed to said parallel planes and extending between said planes, each divider including:
- (1) a rectangular planar member
- (2) means defining a notch removing a corner of said rectangular planar member
- (C) a plurality of separators positioned intermediate said dividers, each including:
- (1) a first surface parallel to and in contact with one of said dividers
- (2) a second surface extending from and perpendicular to said first surface
- (3) a third surface extending from said first surface parallel to and in contact with one of said parallel planes
- (4) means defining a channel portion extending from said second and third surfaces and shaped to accept one edge of the divider adjacent said one of said dividers.
- (D) means for positioning one edge of each of said

6

- dividers relative to one of said parallel planes comprising:
- (1) clip means attached to said divider and extending therefrom parallel to one of said planes
- (2) means extending from said clip in abutting relation with the next adjacent divider.
9. A paper storage system comprising:
- (A) means defining horizontal and parallel top and bottom shelves
- (B) a plurality of dividers parallel to each other and angularly disposed relative to said parallel shelves and extending between said shelves, each divider including:
- (1) a rectangular planar member
- (2) means defining a rectangular notch removing a corner of said rectangular planar member
- (3) said notch removing sufficient material from said corner to reduce the length of one edge of said planar member to the length of one edge of the paper to be stored in said paper storage system
- (C) a plurality of separators positioned intermediate said dividers, each including:
- (1) a first surface parallel to and in contact with one of said dividers
- (2) a second surface extending from and perpendicular to said first surface
- (3) a third surface extending from said first surface parallel to and in contact with said bottom shelf
- (4) means defining a channel portion extending from said second and third surfaces and shaped to accept one edge of the divider adjacent said one of said dividers.
10. A paper storage system comprising:
- (A) means defining horizontal and parallel top and bottom shelves
- (B) a plurality of dividers parallel to each other and angularly disposed relative to said parallel shelves and extending between said shelves, each divider including:
- (1) a rectangular planar member
- (2) means defining a rectangular notch removing a corner of said rectangular planar member
- (3) said notch removing sufficient material from said corner to reduce the length of one edge of said planar member to the length of one edge of the paper to be stored in said paper storage system
- (C) a plurality of separators positioned intermediate said dividers, each including:
- (1) a first surface parallel to and in contact with one of said dividers
- (2) a second surface extending from and perpendicular to said first surface
- (3) a third surface extending from said first surface parallel to and in contact with said bottom shelf
- (4) means defining a channel portion extending from said second and third surfaces and shaped to accept one edge of the divider adjacent said one of said dividers
- (D) means for positioning one edge of each of said dividers comprising:
- (1) clip means attached to said divider and extending therefrom parallel to said top shelf and
- (2) means extending from said clip in abutting relation with the next adjacent divider.
11. A paper storage system comprising:
- (A) means defining horizontal and parallel top and bottom shelves
- (B) a plurality of dividers parallel to each other and angularly disposed to said top and bottom shelves and extending between said shelves, the intersection of the plane of said dividers with the plane of said top

- shelf forming a line having an angle relative to the front edge of said top shelf of less than 90°
- (C) a plurality of separators positioned intermediate said dividers, each including:
- (1) a first surface parallel to and in contact with one of said dividers
  - (2) a second surface extending from and perpendicular to said first surface
  - (3) a third surface extending from said first surface parallel to and in contact with the top surface of said bottom shelf
  - (4) means defining a channel portion extending from said second and third surfaces and shaped to accept one edge of the divider adjacent said one of said dividers.
12. A paper storage system comprising:
- (A) means defining horizontal and parallel top and bottom shelves
  - (B) a plurality of dividers parallel to each other and angularly disposed to said top and bottom shelves and extending between said shelves, the intersection of the plane of said dividers with the plane of said top shelf forming a line having an angle relative to the front edge of said top shelf of less than 90°.
  - (C) a plurality of separators positioned intermediate said dividers, each including:
- (1) a first surface parallel to and in contact with one of said dividers

15

20

25

- (2) a second surface extending from and perpendicular to said first surface
  - (3) a third surface extending from said first surface parallel to and in contact with the top surface of said bottom shelf
  - (4) means defining a channel portion extending from said second and third surfaces and shaped to accept one edge of the divider adjacent said one of said dividers
- (D) means for positioning one edge of each of said dividers comprising:
- (1) clip means attached to said divider and extending therefrom parallel to said top shelf
  - (2) means extending from said clip in abutting relation with the next adjacent divider.
